June 2, 1925.

1,540,324

G. C. FULLER

GAME

Filed Oct. 8, 1921

FIG. 3.

Garth C. Fuller INVENTOR

BY

Herr Papendorf & Hayward
ATTORNEY

UNITED STATES PATENT OFFICE.

GARTH C. FULLER, OF DOUGLASTON, NEW YORK, ASSIGNOR OF ONE-THIRD TO ELMER D. FULLER, OF DOUGLASTON, NEW YORK, AND ONE-THIRD TO NATHANIEL H. FULLER, OF NEW YORK, N. Y.

GAME.

Application filed October 8, 1921. Serial No. 506,304.

To all whom it may concern:

Be it known that I, GARTH C. FULLER, a citizen of the United States of America, residing at Douglaston, in the county of 5 Queens and State of New York, have invented certain new and useful Improvements in Games, of which the following is a full, clear, and exact description.

10 My invention relates to games and more particularly to a card game in which several series of cards bearing different designations are employed to simulate a race between contestants of any kind, either animate or inanimate.

15 The invention consists of a number of series or suits of cards ornamented with racing contestants, the cards of each series or suit being preferably equal in number to that of another suit, each card having certain markings peculiar to its series or suit, one card of each suit serving as a starting or barrier card, and all of the remaining cards being designed to be included in a single pack to be shuffled and played one at 20 a time and laid in appropriate columns to provide a novel and interesting game.

25 The invention also consists in providing in a game of the character referred to above a suitable board on which the game is played, a card ornamented with a starter's device to indicate the point at which the race begins, and another card ornamented with a judges' stand, or other suitable device, to indicate the point or place at which the 30 finish of the race occurs.

The invention is illustrated in the accompanying drawing, in which 35 Fig. 1 is a perspective view of a game board showing the cards in position in longitudinal slots in said board; and Fig. 2 is a fragmentary sectional view on a line of any two columns of cards in Fig. 1; and Fig. 3 is a perspective view of the card deck from which the cards are played.

40 For the purpose of illustrating the present invention, I have shown in the accompanying drawing, playing cards ornamented with racing horses, either by photography, printing, drawing or painting; either natural or grotesque, although it will be understood that the cards may be ornamented with other contestants, either animate or inanimate, for example, bicycles, automobiles, boats, aeroplanes, airships, balloons, etc.

45 In the present instance, four series of 55 cards designated 1, 2, 3, and 4, respectively, shown at A, B, C and D, are provided, although this number may be varied more or less, there being twelve each of the cards numbered 1, 2, 3 and 4, making a total of 60 48 cards in the deck, each card showing a horse in motion. If desired, four cards, that is, one for each series in the deck, for starting purposes may be included in the deck, each card being ornamented 65 with the race horse 1, 2, 3 and 4, respectively, in starting position at the barrier as shown at E, F, G and H in the accompanying drawing. Furthermore, a card shown at I, ornamented with a starting 70 device, is utilized, if desired, to indicate the starting point of the race, and another card shown at J, with a judges' stand, or other suitable device, shown thereon, is utilized to indicate the finish line. 75

The game is played in the following manner:

Four cards numbered 1, 2, 3 and 4 are selected and laid parallel to each other to indicate the start of the race, as shown at 80 E, F, G and H on the drawing. When the barrier cards 1, 2, 3 and 4 are omitted from the deck, one each of the racing cards 1, 2, 3 and 4, shown at A, B, C and D, will be selected and utilized as the starting cards. 85 The remaining playing or racing cards of the series 1, 2, 3 and 4 are then shuffled by one of the players selected as the dealer, who arranges the cards in a deck or pack, shown at O, and the first cards dealt therefrom 90 are laid in a row or column at right angles to the starting line to furnish a track along which the race is to take place, as indicated at K and L. By agreement of the players the length of the race may be indicated by seven or eight track cards, more or less, dealt successively from the deck O, the relative handicaps of the horses being indicated by the numbers or designations of the track cards appearing in the column 95 100

K—L. For example, should there appear in the track, one track card marked 1, two track cards marked 2, four track cards marked 3, and two track cards marked 4, it will be apparent that at the start of the race the horse carrying the number 3 is more handicapped in the forthcoming race by lack of racing cards in the deck remaining to be played than the horses carrying the number 2 and the number 4, and that the said horses number 2 and number 4 are likewise handicapped as compared with the horse carrying the number 1. It will be apparent, likewise, that where no cards of one series appear in the track, say series marked 2, the other horses are accordingly handicapped with respect to that horse.

After the track cards K—L have been laid and the handicaps thus fixed, the dealer then turns up the top racing card in the deck O and places it in its appropriate column parallel to the track cards and proceeds to successively turn up racing cards from the deck and place them in appropriate columns until one of the contestants wins the race which is indicated when the first racing card of one of the series or columns of cards marked 1, 2, 3 or 4 is parallel with the finish line card J. The dealing of the racing cards is continued one at a time until the second and third contestant in like manner have reached the finished line, and the fourth or last horse in the race will then be apparent.

35 A game board is utilized, when desired, on which the game is played, as shown at M, the board being ruled to indicate sections to receive the cards as they are played. Each section is provided with a slit N in which the card is inserted as it is played and serves to hold the card in an upright position, thus simulating an actual race.

I claim:

45 1. Playing cards comprising a plurality of series or suits, each of an equal number of cards all of which cards contain a picture of a common racer, said series of cards each having a common legend thereon, the legend of one series differing from that of another series.

55 2. A racing game comprising a plurality of series of cards, all of said cards containing a picture of a racer, each series comprising the same number of cards as any other series, said series of cards each having a common legend thereon, the legend of one series differing from that of another series, and one card of each series having a legend indicating that it is a starting card.

65 3. Playing cards comprising a plurality of series or suits, each of an equal number of cards, all of said cards containing a picture of a racer, said series of cards each having a common legend thereon, the legend of one series differing from that of another series, one card of each suit having a legend indicating it as a starting card.

4. Playing cards comprising a plurality of series or suits, each of an equal number of cards, all of said cards containing a picture of a racer, said series of cards each having a common legend thereon, the legend of one series differing from that of another series, one card of each suit having a legend indicating it as a starting card and containing a picture of the racer in starting position.

5. Playing cards comprising a plurality of series or suits, each of an equal number of cards, said series of cards each having a common legend thereon, the legend of one series differing from that of another series, one card of each suit having a legend indicating it as a starting card, and other cards of said series or suits selectively constituting a set of track cards, the remaining cards of said series or suits constituting a set of racing cards.

6. A playing card game, comprising a deck consisting of a plurality of series or suits, each of an equal number of cards, said series of cards each having a common legend thereon, the legend of one series differing from that of another series, one card of each suit having a legend indicating it as a starting card, said starting cards being selected from the deck and arranged side by side in a row, a selected number of other cards of said series or suits being dealt from the shuffled deck successively and constituting a set of track cards and as such arranged in a column or row extending at a right angle to the row of starting cards, and the remaining cards constituting a set of racing cards and as such being successively dealt from the said deck and arranged in the order in which they are dealt in column formation with their corresponding starting cards and parallel to the track cards, the card of a series to first appear in its built up column formation parallel to the ultimate built up track card being the winner of the game.

7. Playing cards comprising a plurality of series or suits, each of an equal number of cards, said series of cards each having a common legend thereon, the legend of one series differing from that of another series, one card of each suit constituting a set of starting cards, and other cards of said series or suits selectively constituting a set of track or handicap cards, the remaining cards of said series or suits constituting a set of racing cards.

8. A playing card game, comprising a deck consisting of a plurality of series or suits, each of an equal number of cards, said series of cards each having a common legend thereon, the legend of one series differing from that of another series, one card of each suit having a legend indicating it as a starting card, said starting cards being selected from the deck and arranged 5 side by side in a row, a selected number of other cards of said series or suits being dealt from the shuffled deck successively and constituting a set of track cards and as such arranged in a column or row extending at a right angle to the row of starting cards, and the remaining cards constituting a set of racing cards. 10

In testimony whereof I hereto affix my signature.

GARTH C. FULLER.